UNITED STATES PATENT OFFICE.

ROBERT GRAY, OF NEW YORK, ASSIGNOR OF ONE-HALF INTEREST TO
HENRY O. BERNARD, OF BROOKLYN, N. Y.

HEAD-COVERING.

SPECIFICATION forming part of Reissued Letters Patent No. 9,928, dated November 15, 1881.

Original No. 219,462, dated September 9, 1879. Application for reissue filed October 21, 1881.

To all whom it may concern:

Be it known that I, ROBERT GRAY, of the city, county, and State of New York, have invented a new and useful Improvement in Head-Coverings, which improvement is fully set forth in the following specification, reference being had to the accompanying drawing, which represents a sectional side view of a hat embodying my invention.

10 This invention relates to the manufacture of hats, bonnets, or other head-coverings with a top layer of flock.

Hats of this description have been made by applying the flock to a buckram support, but have invariably been stiff, owing to the fact that in order to give the article the required body or strength it was necessary to use a heavy or thick piece of buckram. One objection to this hat is the stiffness referred to, it 15 being desirable in some cases to furnish a soft hat, and another the visibility of the buckram tending to defeat the object of the flock layer, which is to produce a felt-like article.

My invention is a head-covering consisting 20 of a support of buckram or the like, a top layer of flock, and a canton-flannel or other similar lining, whereby the article is rendered capable of taking a soft finish, while both surfaces thereof have the appearance or semblance of 25 felt—one of plain felt and the other of napped felt.

In the drawing, the letter A designates the support; B, the flock layer; and C the canton-flannel or other similar lining.

30 In carrying out my invention I first cement the lining C to a piece of buckram or like fabric by a suitable adhesive substance, with the nap of the lining exposed, and then press the two together, in any usual or suitable manner, to the desired shape. In lieu of canton-flannel the fabric known as "glove-lining"

may be used. I now apply to the buckram a layer of cotton, wool, or other flock, this process consisting in coating the buckram with an adhesive substance and strewing the flock 45 thereon in finely-powdered form. The article is then in a state for trimming.

The buckram A supports both the flock layer B and the lining C, and, being re-enforced by the lining, a light or thin piece of such material 50 may be used, rendering the article pliable or soft, substantially like soft felt. The appearance of the article, moreover, is felt-like, inasmuch as the lining has the semblance of napped felt, and the flock layer that of plain felt.

55 By my invention I get two important results in the manufacture of head-coverings: First, by combining the lining with thin buckram I get a napped felt-like surface, with sufficient body and flexibility in the combined or compound fabric. Second, by combining flock with the thin buckram and attached lining I get as a further result the combination, with the thin buckram, of a plain felt-like surface and a napped felt-like surface, with sufficient body 60 and flexibility in the head-covering. In other words, a thoroughly felt-like article.

65 What I claim as new, and desire to secure by Letters Patent, is—

1. A head-covering consisting of a support of 70 buckram or the like, a top layer of flock, and a canton-flannel or other similar lining, substantially as and for the purpose described.

2. A head-covering lined in semblance of 75 napped felt, with nap-exposed canton-flannel or the like, substantially in the manner described.

ROBERT GRAY.
